H. A. W. WOOD & C. NORDFORS.

SHEET COUNTING DEVICE.

APPLICATION FILED JAN. 17, 1914.

1,273,438.

Patented July 23, 1918.

UNITED STATES PATENT OFFICE.

HENRY A. WISE WOOD, OF NEW YORK, N. Y., AND CONRAD NORDFORS, OF JERSEY CITY HEIGHTS, NEW JERSEY, ASSIGNEES, BY MESNE ASSIGNMENTS, TO WOOD NEWS-PAPER MACHINERY CORPORATION, OF NEW YORK, N. Y., A CORPORATION OF VIRGINIA.

SHEET-COUNTING DEVICE.

1,273,438.

Specification of Letters Patent. Patented July 23, 1918.

Application filed January 17, 1914. Serial No. 812,724.

To all whom it may concern:

Be it known that we, HENRY A. WISE WOOD and CONRAD NORDFORS, citizens of the United States, said Wood residing at New York, in the county of New York and State of New York, and said Nordfors residing at Jersey City Heights, county of Hudson, and State of New Jersey, have invented a new and useful Sheet-Counting Device, of which the following is a specification.

This invention relates to a device for counting sheets for use upon a rotary web printing press and has for its principal object to provide very simple means for counting folded products at high speeds without the use of reciprocating parts.

Reference is to be had to the accompanying drawings in which—

Figure 1 is a side elevation of the delivery end of a web press showing a preferred embodiment of this invention;

Fig. 2 is an end view of a portion of the same;

Fig. 3 is a fragmentary side elevation showing one position of the counting device, and

Fig. 4 is a similar view showing another position thereof.

As is well understood in this art folded papers have been fanned out on running belts and every fiftieth or one hundredth sheet thrown forward out of position by reciprocable fingers at the rear for the purposes of separating the sheets into bundles and thus counting them. This invention is designed for the purpose of supplanting this reciprocating mechanism and substituting for it extremely simple mechanism capable of operating without undue strain, at the high speeds at which modern presses of certain types are run, and yet having means for preventing the displacement of the last sheet of each bundle.

The invention is shown in the drawings as used in connection with a form of delivery and associated mechanism similar to those shown in the applications of Henry A. Wise Wood, on a bundling delivery for folders, Serial No. 723,284, filed October 1, 1912, and method of delivering folded sheets and apparatus therefor, Serial No. 773,918, filed June 16, 1913. In this mechanism, the folded product is delivered in a well known manner from a folding and cutting cylinder

10 and passes through rollers 11 and fans 55 12 to delivery tapes or belts 13. The fans 12 are shown as on a shaft 14 driven by the gearing which drives the cutting cylinder. The shaft 14 by means of a vertical shaft 15 and suitable gearing, drives a shaft 16. 60 The belts 13 are driven from this shaft directly.

Stationary curved guides 17 are shown for guiding the sheets as they are lowered by the fans. The lower ends of the guides 65 17 are bent in such a manner as to form a pocket between the delivery belts and guides of sufficient size and shape to allow only one paper to enter at a time and to prevent buckling as set forth in one of the above 70 mentioned applications.

Mounted on the shaft 16 and interposed among the fan blades 12 are the rotary counters 22. These not only form means for counting the papers but also serve as a 75 stop for them as the fans deliver them on the delivery belts 13. The counters 22 are of a general circular shape, but each is provided with an eccentric projection 23 extending beyond the circumference of the circular part of the counter. This projection is connected with the circular portion of the counter by a gradual curve or rise on the forward side and by a sharp drop on the rear side. They are geared with respect to 80 the folding cylinder in such a way that they make one revolution for fifty or one hundred papers delivered to the belts according to the number that are to be counted off in each bundle. 90

The operation is very simple. As the sheets are delivered around the guides on the delivery belts, they strike the circular part of the counter one by one and are forwarded on the belts evenly spaced. This 95 continues until the projection 23 comes into contact with the on-coming sheets. Then the last few sheets are pushed forward with a gradual increase which reaches its maximum as the fiftieth sheet is delivered, if 100 that is the number in a bundle. This operation is indicated in Fig. 3.

When the fifty-first sheet is delivered the horn or projection 23 has already passed below the delivery belts 13. This allows 105 this sheet to be deposited back against the circular portion of the counter as shown in Fig. 4. A considerable space is thus formed

between the fiftieth and fifty-first sheets, thus enabling the operator to remove the papers in bundles of fifty. It will be understood of course that the counter can be made 5 and geared up to operate for the purpose of delivering any desired number of sheets for a bundle.

It will be seen therefore that this operation is performed by reducing the mechanism absolutely to its simplest terms. There 10 is no part that moves independently of a rotating shaft for the purpose of performing this counting operation and consequently, no part that is in that sense movable. In other words, the whole counting 15 device rotates positively and rigidly with the shaft and thus there are no joints, connections or other features that can get out of order by rapid operation and nothing that 20 can prevent the speeding up of the press to an extremely high speed. This invention is designed not only to take care of the present high speeds but to provide for future increases.

25 Although we have illustrated and described only a single embodiment of the invention, we are aware of the fact that many modifications can be made therein by any person skilled in the art without departing 30 from the scope of the invention as expressed in the claims, therefore, we do not wish to be limited in these respects, but what we do claim is:—

1. The combination with a fan delivering 35 device and belts for receiving sheets therefrom, of a shaft rotatable constantly at a speed proportionate to that of the fan, and circular plates fixed to the shaft and having eccentric projections for shifting a sheet 40 periodically as delivered on the belts.

2. The combination with a rotary folding cylinder for a rotary web printing press, of delivery belts, rotary means geared to operate with said cylinder for delivering the 45 sheets one at a time therefrom to the belts, a shaft geared to operate with said rotary means, and means fixed to said shaft for

arresting the sheets as delivered to said belts at the same point and separating them into sets of a definite number each by moving 50 forward the last few sheets of a set.

3. The combination with a delivery device for a rotary web printing press, of a shaft connected therewith and operating at a speed proportional to the speed of the delivery device, and means fixed to said shaft for receiving the edge of each sheet as delivered and separating the edge of one sheet periodically from the edge of the next sheet for the purpose of equally spacing the sheets 60 and for thereafter suddenly moving forward some of the sheets to separate them into sets of bundles of a definite number each.

4. The combination with delivery belts, and a rotary fan delivery, of a rotary counting device positively geared up to said fan delivery and having an eccentric projection for shifting a sheet forward periodically, and means for preventing said shifted sheets from slipping over said projection.

5. The combination with a rotary sheet delivering fan and belts in position for receiving sheets from the fan, of means for stopping the forward ends of the sheets as they are delivered on the belts and separating them into bundles, of a guide in position for preventing the last sheet of a bundle from moving over said separating means while on the belts.

6. A counting device for a rotary web 80 printing press comprising a shaft, and a circular plate thereon in position for its edge to engage the sheets and having an eccentric projection for pushing the sheets away periodically.

In testimony whereof we have hereunto set our hands, in the presence of two subscribing witnesses.

HENRY A. WISE WOOD.
CONRAD NORDFORS.
